UNITED STATES PATENT OFFICE

1,994,455

WINDING MACHINE

Edward J. Abbott, Wilton, N. H., assignor to Abbott Machine Company, Wilton, N. H., a corporation of New Hampshire

Application October 15, 1930, Serial No. 488,889

6 Claims. (Cl. 242—35.5)

This invention relates to textile machines and is particularly applicable to machines having circulatory carriers for winding yarn masses, and mechanism for winding yarn on the masses during circulatory motion of the carriers to form traverse-wound headless self-sustaining packages or cheeses, such for example as disclosed in my Patent No. 1,609,639, the patent of E. J. and W. G. Abbott, No. 1,700,425, and my copending application, Serial No. 476,776, entitled Method and machine for preparing yarn packages, filed August 21, 1930.

Objects of the present invention are to provide improved mechanism adapted to drive the traveling yarn masses during a portion only of their circulating path, and to control the stopping and starting of rotation of the yarn masses in such a way as to prevent undesirable variation in the shape or construction of the winding yarn masses (particularly the typical cross-wound construction just described) or unnecessary breakage of the yarn strand leading thereto, and further to provide devices particularly adapted to cause the quick stoppage of the winding mass and devices particularly adapted to cause the controlled initiation of winding without causing breakage of the yarn strand.

Other objects of the invention, advantages and structural improvements will appear from a consideration of this specification wherein a machine embodying the present invention is explained by way of example.

In the drawings:

Fig. 1 is a plan view of a traveling spindle winding machine with its traveling units omitted, showing the present invention applied thereto;

Fig. 2 is a fragmentary left side elevation of a portion of the machine of Fig. 1 and of one of the traveling winding units thereof, showing the present invention applied thereto; and

Fig. 3 is a vertical sectional view taken on line 3—3 of Fig. 1.

Fig. 1 illustrates the machine in its preferred form, which in the general arrangement of its parts and in general function may resemble the machines disclosed in the above mentioned patents and applications. Thus in common with these machines the present machine includes a guideway constituted of upper and lower rails mounted on upright frame elements, the upper rails 4 being shown in the drawings, a plurality of carriers 10 for the yarn being operated on, (one only of these carriers being shown in Figs. 2 and 3), and a drive chain 30 running on sprock-

et wheels 36, 36^a for causing the carrier to travel in the path defined by the guideway. Suitable driving connections for rotating sprocket wheel 36 may be those of my application, Serial No. 476,776 as illustrated and described in my Patent No. 1,911,047, a division of the present application.

A suitable carrier 10 for the yarn may include an upright plate 60 (Figs. 2 and 3) adapted to bridge the distance between the rails of the guideway and may be provided with suitable anti-friction rolls including rolls 97 adapted to roll on upper rail 4. The upper end of the plate 60 may bear an upper head portion 65 to which are attached vertical plates 66 and 67. Plate 66 preferably extends upward as indicated at 68 and is provided at its upper end with a suitable bearing adapted to receive the bifurcated end of a package-carrying arm 71 pivotally mounted thereon, to swing transversely to the direction of movement of the carrier. The winding package C is adapted to be formed upon a tube or cone 72^a rotatably carried by a spindle 72 which is suitably clamped in the outer or free end of the arm 71.

The lower portion of the plate 60 of the carrier 10 is preferably provided with a spindle adapted to carry a supply package or unwinding mass of yarn. From such supply package or mass, the strand of yarn Y is shown as conducted upward between suitable guide wires 396 and 397, between tension disks 380 and 381, and between the opposed blades 400 and 401 of a slab catcher to the winding package, these devices being conveniently mounted on a cover plate 110 of the carrier.

Means is provided for rotating the winding package of yarn as the carrier progresses along the guideway, and by way of example such means is shown as comprising a pair of rotary drive rolls 50, 51, mounted in bearing housings of which two are indicated at 52^a (Fig. 1), the rolls being disposed above the straight portions of the rail 4 in position to contact with and rotate the winding package C when the arm 71 is swung in a counterclockwise direction in Fig. 3. Suitable driving connections for these rolls may comprise the connections described and illustrated in my divisional Patent No. 1,911,047.

The illustrated embodiment of the invention is particularly adapted for the winding of headless, self-sustaining Fiji packages or cheeses consisting of layers of reversed spiral windings, with the cusps formed by the reversals of the spirals defining the end faces of the package. This man-

ner of winding necessitates a rapidly moving traverse device adapted to engage the yarn strand Y as it approaches the winding mass. Such a device is shown herein as a traverse cam 70 (Fig. 2) 5 rotatably mounted between the plates 66 and 67 of the carrier and spirally grooved to reciprocate a cam follower 101, which is slidably mounted on a horizontal rod 100^a (Fig. 3), and which carries an upward extending grooved eye 106 engageable with the yarn strand. Suitable driving connections for the traverse cam may include 10 tires 71 thereon which engage and are turned by drive rolls 50 and 51 successively, as the carrier moves around the guideway.

15 In the travel of the carriers around the guideway it is desirable to stop the driving of the winding yarn mass and traversing of the yarn so as to permit the performance of replenishment operations with respect to the yarn masses on 20 the carriers, either manually, or automatically as in the machine of Patent No. 1,700,425. Preferably the stoppage of driving for these purposes is controlled by means responsive to the attainment by the carrier of a predetermined point on 25 the guideway, or responsive to the completion by the carrier of a predetermined course of travel. Means for causing such cessation of driving and traversing may comprise a dog 362 carried in an enlarged head 360 of a horizontal shaft 303 on 30 the carrier and adapted to strike in passing, and to be rotated by, a pin 307 extending from the guideway, thus to turn shaft 303 and a crank 302 to raise a lifter rod 301 and swing the package carrying arm 71 and package C clockwise (as 35 viewed in Fig. 3) through the full-line position of Fig. 3 into the outermost broken line position of that figure.

As explained in my copending application Serial No. 476,776, the dog 362, lifter rod 301 and 40 their connections may serve also to shift the position of the yarn package upon the occurrence of improper conditions in the winding strand Y. Such improper conditions may comprise for example the appearance in the traveling strand of 45 slubs or imperfections which it is desired to remove, or the cessation of proper travel of the yarn such as evidenced by excessive or insufficient tension in the strand, breakage of the yarn, or exhaustion of the supply yarn. As exemplifying 50 one type of detector particularly suited to detect breakage or exhaustion, the present machine may be equipped with a pivotally mounted wire bail 310 normally held depressed by the yarn strand Y, and in such position acting through a link 314 to hold dog 362 in an inclined position. The 55 guide rail 4 of the machine is preferably provided with a number of short pins 318, which are normally cleared by dog 362, one such pin 318 being indicated in Fig. 2. Upon the occurrence 60 of exhaustion or breakage of the yarn, the yarn-contacting portion of the detector wire 310 rises, thus permitting dog 362 to drop into a vertical plane. In such position the dog strikes in passing, and is rotated by the next adjacent pin 318, 65 thus actuating the above described connections to cause cessation of driving the package and traversing of the yarn.

Considering now more particularly a carrier reaching the pin 307 disposed near the end of a 70 straight portion of the guideway, (Figs. 1, 2 and 3), the pin 307, dog 362, shaft 303, crank 302 and lifter rod act to swing the package carrying arm and package C clockwise toward the inactive position of Fig. 3; accordingly traversing of the 75 strand ceases. Were the yarn package C to be

allowed to rotate after driving stops, (as would normally happen) a strand, no longer traversing, would wind about a single section of the length of the package, thus producing an enlargement or bung which would destroy the regularity of subsequent layers and impair the compactness and self-sustaining qualities of the package. To prevent this, I provide a package brake 5 adapted rapidly to stop the rotation of the winding yarn package, preferably operable on the package as a consequence of, and during, the shifting of the package incident to stopping of driving of the package and traversing of the 10 yarn.

Referring to Figs. 1, 2 and 3, wherein the package brake is shown in its preferred arrangement as disposed to act on the yarn packages of successive carriers as the carriers are about to leave the end of drive roll 51 in approaching the operator's end of the machine, the brake 80 is shown 15 as formed of a sheet metal plate yieldingly mounted to intersect the path traveled by various sized packages as the packages are swung to their inactive positions. As shown in Fig. 2, the brake 80 is preferably pivotally mounted upon a generally horizontal rod 81 extending generally parallel to the path of the yarn packages, this rod 20 81 being herein shown as supported by a bracket 82 fastened to the upper rail 4 of the guideway. Preferably the brake 80 is yieldingly held in its 25 lowermost position of Fig. 3 by gravity, the brake having a weight 84 mounted thereon, and is prevented from falling below this position by the provision of a limiting stop constituted of a lug 30^a movable with the brake element and adapted 35 to strike a pin 80^b fast with the rod 81.

As the carrier reaches pin 307 (Fig. 3) on the guideway, the dog 362 is temporarily retained by the pin and thus causes shaft 303 and crank 302 to swing, lifting the rod 301 and swinging the 40 package-holding arm 71. As the winding package rises from the drive roll 51, the periphery of the package C is rubbed against the weighted 45 brake 80 which quickly stops rotation of the package. Thus in the illustrated machine but little untraversed yarn is wound on the package after the yarn is disengaged from the traverse eye 106.

In order to permit the brake 80 to be adjusted 50 vertically, or to be adjusted angularly so as better to accommodate conical yarn packages when these are wound, the rod 81 on which the brake is mounted is preferably connected to the bracket 82 by means of an adjustable arm 85 secured thereto by a bolt 86, passing through a slot 87 in the bracket 82. The brake is preferably provided with an inclined extension 88 at its leading edge as shown in Figs. 2 and 3 adapted to engage the end of the cylindrical periphery of a 55 very large package which may happen to pass the brake in an elevated or inactive position, so that the brake is lifted by camming action of such a package, instead of being struck at a thin edge of the sheet material. Preferably the free outer edge of the brake 80 is turned up as indicated at 89, to permit the braked package to slide 60 smoothly from under the brake.

By virtue of the pivotal mounting of the brake 65 this device is adapted to operate on packages of various sizes encountered as successive carriers 70 pass with their packages in varying states of completion.

After its rotation has been stopped by the 75 brake 80, the package may then pass a suitable gage 250 which marks it with chalk or the like

if the package has attained full size; then the winding unit may pass a pair of air nozzles 220, 221 which are directed respectively at the traverse eye 106 and associated parts, and at the guide wires 396, 397, the tension disks 380, 381 and the slab-catching blades 400, 401. After the unit has passed the semi-circular end portion of the guideway, it may pass a lubricator tube 231 carrying a lubricator brush 230 which oils the traverse guide rod 100^a and associated parts. Thereupon the winding package may be lowered onto the drive roll 50 and started winding by the mechanism described and claimed in my divisional Patent No. 1,911,047. The air cleaning means and the lubricating means form the subject matter of my continuing applications Serial Nos. 577,057 and 577,055, both filed November 24, 1931.

It should be understood that the present disclosure is for the purpose of illustration only and that this invention includes all modifications and equivalents which fall within the scope of the appended claims.

I claim:

- 25 1. A textile machine including a carrier for a winding package of yarn, means for moving the carrier in a predetermined path with relation to the machine, means for rotating the package to wind yarn thereon during such motion, a brake adapted to stop rotation of the package, mechanism on the carrier for causing the package to be acted on by the brake, and means, operated by the relative movement of the carrier with relation to the machine, for actuating said mechanism.
- 30 2. A textile machine including a carrier for a winding package of yarn, means for moving the carrier in a predetermined path with relation to the machine, means for rotating the package to wind yarn thereon during such motion, and means for braking the rotation of the package, said braking means including a brake element stationed adjacent to said path and package-shifting means for moving the package into contact with said brake element, said package-shifting means including an element on the car-

rier adapted to be moved relative to the carrier by forward movement of the carrier and a connection from said element to the package.

3. A textile machine comprising means for causing a plurality of rotating strand packages to travel in a procession during rotation thereof, and means for rotating said packages during such travel, in combination with a brake element located adjacent to the path of travel of said packages, and means for shifting the traveling packages successively toward said brake element to cause the traveling packages successively to be braked by said element.

4. A textile machine comprising means for rotating a plurality of strand packages, and means for causing said packages to travel in a path during such rotation, and a brake element located adjacent to said path and adapted to act on successive packages to stop their rotation, said brake element having a motion transverse to said path whereby to accommodate successive packages of various diameters.

5. A textile machine comprising means for causing a plurality of rotating strand packages to travel in a procession during rotation thereof, and means for rotating said packages during such travel, in combination with a brake element located adjacent to the path of travel of said packages, and means for causing said brake to be applied to the traveling packages successively including means whereby the brake element can move away from the axes of the packages to rest on the peripheries of different sized packages successively presented thereto.

6. A textile machine comprising means for causing a plurality of rotating strand packages to travel in a procession during rotation thereof, means for rotating said packages during such travel, and a brake adapted to be engaged by the packages successively passing said brake, said brake including a cam surface disposed to engage a package too large otherwise to pass said brake, and a mounting for the brake permitting it to be moved by contact of the package with said cam surface so as to permit passage of the package.

EDWARD J. ABBOTT.
